UNITED STATES PATENT OFFICE.

ELIAS GUNNELL, OF MANITOWOC, WISCONSIN, ASSIGNEE OF ONE-HALF TO MANITOWOC DRY DOCK COMPANY, OF MANITOWOC, WISCONSIN, A CORPORATION OF WISCONSIN, AND ONE-HALF TO WILLIAM CLIFFORD, OF DULUTH, MINNESOTA.

ANTIDRIFTING DEVICE.

No. 923,648.

Specification of Letters Patent.

Patented June 1, 1909.

Application filed November 20, 1907. Serial No. 403,014.

To all whom it may concern:

Be it known that I, ELIAS GUNNELL, a citizen of the United States, residing at Manitowoc, in the county of Manitowoc and State of Wisconsin, have invented certain new and useful Improvements in Antidrifting Devices, of which the following is a specification.

The invention relates to anti-drifting devices and particularly to such devices as applied to dump scows. Boats of this general type are flat bottomed and have no rudder. Consequently difficulty is encountered in towing them from a tug, as the line used affords poor control when there is any wind or current tending to swing the scow around. The object of the invention is to provide improved means whereby the scow may be effectively controlled by the tug irrespective of current and wind, and to this end the invention comprises a drag means at the rear end of the scow for retarding its movement whereby the line from the tug at the front end of the scow may easily and positively control its movements. Certain embodiments of the invention are illustrated in the accompanying drawings, wherein:

Figure 1 is a side elevation of the scow provided with my invention together with the towing tug attached thereto,

Figure 2 is a plan view of the scow,

Figure 3 is an enlarged longitudinal section through one end of the scow,

Figure 4 is a transverse section on the line IV—IV of Figure 3,

Figures 5, 6, 7 and 8 are views corresponding to those of Figures 1, 2, 3 and 4, but having a modified form of a resisting device and operating means therefor,

Figure 9 is an enlarged detail section on the line IX—IX of Figure 8, and

Figure 10 is a transverse section on the line X—X of Figure 2.

Referring to the drawings, 1 is the scow which is of the ordinary type and comprises a pair of side portions 2¹, 2² connected together by bulkheads and divisional walls forming a pocket 2¹ into which the material to be dumped is loaded.

Extending nearly the entire length of the scow and intermediate the side members is the usual well 2, into which the material loaded is finally dumped through the doors 2³.

It is in this well or passage that my anti-drifting device is located. This device consists of a pair of swinging flaps 3, which flaps are located at both ends of the scow, and are adapted to lie either in the position shown in Figures 3 and 4, at which time they extend across the well, and act as retarding devices, 55 or in positions at right angles to that occupied in Figures 3 and 4, at which time they will lie against the sides of the wall and permit the free passage of the water therethrough. The flaps are operable from the 60 top of the scow by means of the shafts 4, carrying at their upper ends the levers 5. Stuffing boxes 6 are provided in the bottom of the scow in order to make a tight connection between such bottom and the shafts 4. 65 It will be understood that the flaps at the rear end of the scow are placed in operative position, when the scow is going ahead, and at this time the flaps at the front end of the 70 scow are open or in inoperative position to 75 permit the free passage of water through the well, and when the direction of movement of the scow is reversed, the positions of the flaps at the end are reversed.

The form of construction shown in Figures 80 5, 6, 7, 8 and 9 differs from that of Figures 1, 2, 3 and 4, in that the retarding flaps are 85 swung from their upper horizontal edges instead of their vertical edges, and the means for swinging these flaps is different from that shown in the other form. Referring particularly to Figures 7 and 8, it will be noted that the flap 3¹ is hinged at its upper edge 7, and is swung by means of the cables 8 attached to the opposite sides of the lower edge 90 of the flap and secured at their upper ends to the sprocket chains 9. The sprocket chains 9 engage the sprocket wheels 10 mounted upon the shaft 11 which in turn is carried by the standards 12. The shaft 11 is rotated 95 and locked in position by means of the mechanism shown in Figure 9, which mechanism consists of the ratchet wheel 13, the dog 14 having a slight rotative movement about the pin 15, the operating lever 16 pivoted to the lug 17 at its lower end, and carrying above such lower end the pair of levers 18, which levers are connected by means of the pin 19 in position to engage the teeth of the ratchet. On a downward movement of the 100 handle 16 the pin 19 engaging one of the

105

teeth of the ratchet, carries it ahead, thus 45
rotating the shaft 11. The movement of the
handle is then reversed, the dog 14 holding
the ratchet from reverse movement until a
5 new grip upon the ratchet 13 is secured. It
will be seen that when the flaps 3 and 3' at
the rear end of the scow are in operative position
extending transversely across the well
2, the movement of such rear end of the scow
10 is retarded so that positive control of the
front end is secured by means of the tow
line, and as a result the scow may be pre-
vented from drifting and given any desired
course. When there is no adverse current
15 or wind, the flaps at both ends are kept in
inoperative position.

Having thus described my invention and
illustrated its use, what I claim as new and
desire to secure by Letters Patent is the fol-
20 lowing:

1. The combination with a scow having a
longitudinal open bottomed well, of an anti-
drifting flap movably mounted in such well
and adapted in one position to lie across the
25 well to retard the longitudinal movement of
the boat and in another position to permit
the water to pass it freely, and means for
holding the flap in retarding position.

2. The combination with a scow having an
30 open bottomed dumping well extending
throughout the length of the bottom of the
scow, of an anti-drifting flap lying across the
well and hinged along its upper edge, and
means whereby the flap may be held in posi-
35 tion to obstruct the passage of water through
the well.

3. The combination with a scow having an
open bottomed dumping well extending
40 throughout the length of the bottom of the
scow, of an anti-drifting flap lying across the
well and hinged along its upper edge, and
means whereby the flap may be held either
in obstructing position across the well or

folded to permit the free passage of water
through the well.

4. The combination with a scow having an
open bottomed dumping well extending
45 throughout the length of the bottom of the
scow, of an anti-drifting flap lying across the
well and hinged along its upper edge, an op-
erating gear on the deck of the scow, and
flexible connecting means passing over the
50 gear and connected to the opposite sides of
the flap for moving such flap to any desired
position.

5. The combination with a scow having an
open bottomed dumping well extending
55 throughout the length of the bottom of the
scow, of an anti-drifting flap lying across the
well and hinged along its upper edge, and op-
erating means whereby the flap may be
moved to and held in any desired position.

6. The combination with a scow having an
open bottomed dumping well extending
65 throughout the length of the bottom of the
scow, of an anti-drifting flap lying across the
well and hinged along its upper edge, and
means operable from the deck of the scow
whereby the flap may be moved to and held
70 in any desired position.

7. The combination with an anti-drifting
flap swinging about a horizontal axis, of op-
erating means therefor comprising a flexible
connection to the opposite sides of the flap, a
sprocket over which the flexible connection
75 passes, an operating ratchet for the sprocket,
a handle provided with a pivoted operating
pawl engaging the teeth of the sprocket, and
a holding pawl for the ratchet.

In testimony whereof I have hereunto
signed my name in the presence of the two
subscribed witnesses.

ELIAS GUNNELL.
